(57) **ABSTRACT**

A dual-radiator whip antenna to operate over a 30 to 450 MHz frequency band includes a high frequency dipole above a low frequency monopole. The outer conductor (30) of a coaxial line is configured to operate as a monopole. Above the upper terminus of the outer conductor, an extension (32a) of the inner conductor (32) is configured as the upper arm of a dipole. An upper length of the outer conductor also functions as the lower dipole arm. With a single antenna port (13), a diplexer and other feed elements separate signals into high and low frequency bands respectively coupled to the dipole and monopole radiators. Increased high frequency range results from positioning of the center of radiation of the dipole above the monopole.

BACKGROUND OF THE INVENTION

This invention relates to antennas and, more particularly, broadband whip antennas providing improved performance.

The design and implementation of many varieties of whip antennas are well known. The general-usage dictionary definition of "a flexible radio antenna" encompasses the typical configuration of a base-supported flexible upright element of extended length. The *IEEE Standard Dictionary of Electrical and Electronic Terms* is more specific in its reference to "a thin flexible monopole antenna". Prior types of whip antennas are suitable for many applications, subject to inherent limitations such as range of coverage and usable frequency band for an individual antenna design.

Objects of the present invention are, therefore, to provide new and improved whip antennas and such antennas having one or more of the following characteristics and advantages

15:1 bandwidth (e.g., 30 to 450 MHz);
broadband dual radiator construction, dipole above monopole;
dual-point-feed, bands separated for dipole and monopole;
elevated, high frequency dipole for increased range;
coaxial construction, with outer conductor forming low frequency monopole;
coaxial high and low band radiators;
dipole above monopole in single elongated radome;
single port input/output at antenna base;
diplexed feeds to high and low band radiators;
simplified, low cost construction; and
readily mountable on a vehicle or other support structure.

SUMMARY OF THE INVENTION

In accordance with the invention, a dual-radiator whip antenna includes a vertically-extending concentric structure. An outer element circumferentially surrounds an inner conductor, with the outer element configured to provide a first radiating element (monopole) operable over a first frequency band. The inner conductor has an upper extension extending vertically beyond the upper terminus of the outer element, with the upper extension configured to provide a second radiating element (dipole) operable over a second frequency band. A feed configuration is arranged to couple first signals within the first frequency band to the outer element and couple second signals within the second frequency band to the upper extension. The feed configuration may include: a diplexer coupled to an antenna port to separate signals into first signals at a first diplexer port and second signals at a second diplexer port; a lower feed circuit at the base of the antenna to couple signals from the first diplexer port to the outer element and signals from the second diplexer port to the inner conductor; and an upper feed circuit coupled between the upper terminus of the outer element and the upper extension of the inner conductor to excite the second radiating element.

For a better understanding of the invention, together with other and further objects, reference is made to the accompanying drawings and the scope of the invention will be pointed out in the accompanying claims.

5

BRIEF DESCRIPTION OF THE DRAWINGS

FIG. 1 is an external view of a form of dual-radiator whip antenna pursuant to the invention, including block diagram representation of feed configuration elements.

10

FIG. 2 is a conceptual diagram of the FIG. 1 whip antenna, with circuit representations of portions thereof included in FIGS. 2A, 2B, 2C and 2D.

15

FIG. 3 shows a coaxial transmission line formed to provide basic portions of the FIG. 1 antenna, with inclusion of circuit elements represented pursuant to FIGS. 2, 2A, 2B, 2C and 2D.

DESCRIPTION OF THE INVENTION

FIG. 1 is an external view of an embodiment of a dual-radiator whip antenna 10 pursuant to the invention. This antenna was designed to cover a 15:1 bandwidth for radiation and reception of signals over a frequency range of 30 to 450 MHz. The antenna 10 includes a base-mounted vertically-extending concentric structure 12, which in FIG. 1 is covered by a weather-resistant, radiation-transmissive covering (e.g., a radome of generally circular cylindrical shape). As will be described, radome 12 houses vertically-stacked first and second radiating elements. Antenna 10 also includes a feed configuration comprising units 14, 16 and 18 visible in FIG. 1, as well as additional components, such as lower and upper feed circuits, to be addressed below.

Diplexer 14 is a frequency diplexer coupled to antenna port 13 and arranged to separate input signals into first signals (e.g., signals in a first frequency band of 30 to 160 MHz) provided at first diplexer port 15a and second signals (e.g., signals in a second frequency band of 160 to 450 MHz) provided at second diplexer port 15b. SWR control unit 16 is provided to improve antenna standing wave ratio (SWR) characteristics by introducing appropriate frequency-dependent signal attenuation and may include separate sections (one for each of the frequency bands) connected respectively to ports 15a and 15b. Impedance transformer unit 18 is provided to improve impedance matching and may include separate transformer sections (one for each of the first and second radiating elements) coupled respectively to ports 15a and 15b, via unit 16 as shown. In this configuration, unit 18 is also coupled to the radiating elements via terminals 20 and 22 and feed circuits to be further described. Once having an understanding of the invention, units 14, 16 and 18 can be provided by skilled persons using existing technology or, in some applications, one or more of these units may be omitted as unnecessary.

FIG. 2 is a conceptual diagram of the FIG. 1 antenna with the radome and units 14, 16 and 18 removed. On an overview basis, the vertically-extending concentric structure 12 has the form of a coaxial transmission line section (e.g., section of coaxial cable) including an outer conductor 30 and inner conductor 32. Outer conductor 30 extends to a height of 83 inches above the base in this example (all lengths stated approximately) and is utilized as a monopole radiating element over the first frequency band of 30 to 160 MHz. Inner conductor 32 extends through outer conductor 30 to a height of 83 inches and has an upper extension 32a reaching a height of 95 inches. As will be described, upper extension 32a is configured for operation as a dipole utilizing upper extension 32a as an upper dipole arm and the

upper length of outer conductor **30** (its length extending between the 71 and 83 inch heights) as a lower dipole arm. Upper extension **32a** may be an exposed section of coaxial cable inner conductor or other appropriate conductive member. Operationally, the effective length **31** of the monopole first radiator comprising outer conductor **30** will typically include upper extension **32a** (which is radiation excited in monopole operation, in this embodiment) and thereby extend to an approximate height of 95 inches. Also, operationally the effective length **33** of the dipole second radiator comprising upper and lower dipole arms, as described, will have an approximate length of 24 inches, extending from 71 to 95 inches above the base. The center of radiation for the dipole element will thus be elevated 83 inches above the base of the antenna, providing increased coverage (e.g., 6 dB gain improvement over a dipole mounted at antenna base level). With this construction, the dipole element operates essentially independently of any ground plane (vehicle or other surface) above which the antenna extends.

As shown in FIG. 2, the dual-radiator whip antenna comprises a vertically-extending concentric structure in the form of a coaxial transmission line section (e.g., a section of coaxial cable of suitable characteristics) with cylindrical outer conductor **30** shown dashed and inner conductor **32**. Conductor **30** is an outer element circumferentially surrounding inner conductor **32**, with element **30** configured to provide a first radiating element (i.e., a monopole) operable over a first frequency range of 30 to 160 MHz in this example. Conductor **32** has an upper extension **32a** extending above the upper terminus (i.e., terminus at height 83 inches) of outer element **30**. The upper extension **32a** is configured to provide a second radiating element (i.e., a dipole) operable over a second frequency range of 160 to 450 MHz in this example. As already noted, upper extension **32a** functions as an upper dipole arm and the upper length of conductor **30** between heights of 71 and 83 inches functions as a lower dipole arm.

FIGS. 2A, 2B, 2C and 2D are simplified circuit representations of portions of the FIG. 2 antenna. FIG. 2A illustrates a lower feed circuit in the form of a dual feed/choke circuit used at block A at the base of the FIG. 2 antenna. Terminal **22** couples high frequency signals in the 160 to 450 MHz second frequency range (provided by diplexer **14**, see FIG. 1) to the inner element **32**. Terminal **20** couples low frequency signals in the 30 to 160 MHz first frequency range (provided by diplexer **14**) to the outer element **30** via inductance **L1**. While the outer conductor **30** is coupled to reference potential or ground via the parallel **C1/L2** circuit, that circuit has reactance values selected to perform as a choke isolating the 30 to 160 MHz signals from ground. The lower feed circuit of FIG. 2A is thus effective to couple signals from the first diplexer port **15a** to the outer element **30** (via terminal **20**) and signals from the second diplexer port **15b** to the inner element **32** (via terminal **22**).

FIG. 2D illustrates an upper feed circuit coupled between the upper terminus of the outer element **30** and the upper extension **32a** of inner conductor **32**, at block D in FIG. 2, to excite the second radiating element. As shown, the 160 to 450 MHz second frequency range signals are coupled from inner conductor **32** to upper extension **32a** via inductance **L5**. Upper extension **32a** is referenced to outer conductor **30** via the parallel **L6/C3** circuit, which acts as a double tuning circuit for improved performance over the 160 to 450 MHz band. The upper feed circuit of FIG. 2D is thus effective to provide excitation of upper extension **32a** for operation as a dipole constituted as previously discussed.

The FIG. 2, configuration also includes, at block B, an inductance **L3** shown in FIG. 2B which is provided as a

tuning inductance to improve performance of the monopole element **30** over the first frequency band. Included at block C is a parallel **C2/L4** circuit shown in FIG. 2C, which acts as a high frequency choke helping to define the lower dipole arm by isolating the 160 to 450 MHz signals from the portion of outside conductor **30** existing below block C in FIG. 2, while not preventing passage of low frequency signals. In this antenna design, the FIGS. 2B and 2C circuits are positioned at approximately 21 and 71 inches, respectively, above base level. Appropriate reactance values for the capacitances and inductances shown in FIGS. 2A, 2B, 2C and 2D can be specified by skilled persons having an understanding of the invention. Exemplary values are provided below.

Referring now to FIG. 3, there is shown a representation of an antenna implementation pursuant to the invention, wherein a section of coaxial cable is formed to provide certain of the circuit elements discussed with reference to FIG. 2. As illustrated, coaxial connectors **40** and **42** are mounted to a portion of a mechanical configuration **44** at the base of the antenna **10**, which is arranged to enable the antenna to be mounted in an upright alignment and may also house units **14**, **16** and **18** of FIG. 1. The inner conductor of connector **40** represents terminal **20** of FIGS. 1 and 2, and is shown coupled to the outer conductor **30** via a discrete component inductor **L1**, which may be soldered in place. The inner conductor of connector **42** represents terminal **22** of FIGS. 1 and 2A, and connects directly to the inner conductor **32** of the coaxial cable. As represented in FIG. 3, a portion of the coaxial cable is coiled to provide inductance **L2** between the upper part of outer conductor **30** and ground (unit **44**) and the **C1/L2** choke is completed by inclusion of a discrete capacitor **C1** connected across the **L2** coil to ground or reference potential.

Inductances **L3** and **L4**, as shown in FIG. 3, are provided by similarly coiling a portion of the coaxial cable to provide an inductance along the outer conductor **30**. As will be appreciated, once the extent of physical coiling is empirically determined to provide suitable inductances for a particular antenna design, production antennas can readily and economically be fabricated. Coiling of the coaxial cable to provide the desired conductor **30** inductances, will also result in coiling of the inner conductor contained within the cable. However, as shown, there are no capacitances added with respect to the inner conductor and the overall effect on transmission of the high frequency signals within the coaxial cable from terminal **22** will not prevent the desired operation of the upper dipole element as previously described.

With respect to block D of the FIG. 2 antenna, reactances **L5**, **L6** and **C3** are provided in discrete component or other appropriate form at the base of upper extension **32a** as shown in FIG. 3. As discussed, a cylindrical radome will typically be included to encompass and support the antenna when provided in a FIG. 3 or other configuration.

Based on computer analysis, with an antenna as described mounted on a vehicle at a point 14 feet above the ground, projected operating results were as follows for reception from a 100 watt transmitter at a distance of 30 Km. Received power level at the antenna port **13** was indicated at about -125 dBm across the 30 to 160 MHz band and about -100 dBm across the 160 to 450 MHz band. As previously noted, increased coverage in the upper frequency band is provided as a result of the raised position of the high frequency dipole element above the low frequency monopole element. With reference to FIGS. 2A, 2B, 2C and 2D, in this antenna design reactance values were as follows: **L1**, 0.15 μ H; **L2**, 1.00 μ H; **L3**, 0.20 μ H; **L4**, 20.0 μ H; **L5**, 0.02 μ H; **L6**, 0.20

μ H; C1, 3.13 pF; C2, 0.088 pF; and C3, 0.62 pF. A section of flexible coaxial cable with a braided outer conductor and a characteristic impedance of 50 Ohms was used to provide the concentric elements.

While there have been described the currently preferred embodiments of the invention, those skilled in the art will recognize that other and further modifications may be made without departing from the invention and it is intended to claim all modifications and variations as fall within the scope of the invention.

What is claimed is:

1. A dual-radiator whip antenna, comprising:
a vertically-extending concentric structure including
an outer element circumferentially surrounding an inner
conductor, said outer element configured to provide a
first radiating element operable over a first frequency
band, 15
the inner conductor having an upper extension in a fixed
position extending vertically beyond the upper terminus
of the outer element, said upper extension configured
to provide a second radiating element operable
over a second frequency band; and 20
a feed configuration to couple first signals within the first
frequency band to said outer element and couple sec-
ond signals within the second frequency band to said
upper extension, to permit simultaneous use of said first
and second radiating elements, the feed configuration
including 25
a diplexer coupled to an antenna port to separate signals
into said first signals at a first diplexer port and said
second signals at a second diplexer port,
a lower feed circuit at the base of said antenna to couple
signals from the first diplexer port to said outer element
and signals from the second diplexer port to said inner
conductor, and 30
an upper feed circuit coupled between the upper terminus
of the outer element and the upper extension of the
inner conductor to excite said second radiating element.
2. A dual-radiator whip antenna as in claim 1, wherein
said outer element is configured to form a monopole radi-
ating element and said upper extension is configured to form
a dipole radiating element comprising said upper extension
and an upper length of said outer element. 40
3. A dual-radiator whip antenna as in claim 1, wherein
said concentric structure comprises a section of coaxial
transmission line. 45
4. A dual-radiator whip antenna as in claim 3, wherein
said concentric structure additionally provides at least one
inductance comprising a coiled portion of said coaxial
transmission line. 50
5. A dual-radiator whip antenna as in claim 1, wherein
said feed configuration additionally includes impedance
transformer sections to improve impedance matching to said
outer element and inner conductor. 55
6. A dual-radiator whip antenna as in claim 1, wherein
said feed configuration additionally includes frequency
dependent signal attenuation sections to improve standing
wave ratio characteristics affecting signal transmission. 60
7. A dual-radiator whip antenna as in claim 1, additionally
comprising a mechanical configuration at the base of the
antenna to enable the antenna to be mounted in an upright
alignment. 65
8. A dual-radiator whip antenna as in claim 1, additionally
comprising a weather-resistant, radiation-transmissive cov-
ering encompassing the outer element and upper extension
of the inner conductor.
9. A dual-radiator whip antenna as in claim 1, wherein the
first radiating element is configured for operation over a 30
to 160 MHz band and the second radiating element is
configured for operation over a 160 to 450 MHz band.
10. A dual-radiator whip antenna, comprising:
a vertically-extending concentric structure including
an outer element at least partially surrounding an inner
conductor, said outer element configured to provide a
first radiating element operable over a first frequency
band, 10
the inner conductor having an upper extension in a fixed
position extending vertically beyond the upper terminus
of the outer element, said upper extension config-
ured to provide a second radiating element operable
over a second frequency band; and 15
a feed configuration to couple first signals within the first
frequency band to said outer element and couple sec-
ond signals within the second frequency band to said
upper extension of the inner conductor, to permit
simultaneous use of said first and second radiating
elements.
11. A dual-radiator whip antenna as in claim 10, wherein
said outer element is configured to form a monopole radi-
ating element and said upper extension is configured to form
a dipole radiating element comprising said upper extension
and an upper length of said outer element.
12. A dual-radiator whip antenna as in claim 10, wherein
said feed configuration includes
an upper feed circuit coupled between the upper terminus
of the outer element and the upper extension of the
inner conductor to excite said second radiating element.
13. A dual-radiator whip antenna as in claim 12, wherein
said feed configuration includes
a lower feed circuit to couple said first signals to said
outer element and couple said second signals to the
inner conductor.
14. A dual-radiator whip antenna as in claim 10, wherein
said vertically-extending concentric structure comprises a
section of coaxial transmission line.
15. A dual-radiator whip antenna as in claim 14, wherein
said concentric structure additionally provides at least one
inductance comprising a coiled portion of said coaxial
transmission line.
16. A dual-radiator whip antenna as in claim 10, wherein
the inner conductor extends through the outer element over
the length of the outer element and said upper extension is
an extension of the inner conductor having a length suitable
for operation, in cooperation with an upper length of the
outer element, as a dipole radiator at frequencies within the
second frequency band.
17. A dual-radiator whip antenna as in claim 16, wherein
the outer element has a length suitable for operation as a
monopole radiator at frequencies within the first frequency
band.
18. A dual-radiator whip antenna as in claim 10, wherein
said feed configuration includes a diplexer to separate sig-
nals input at an antenna port into first frequency band signals
provided at a first diplexer port and second frequency band
signals provided at a second diplexer port.
19. A dual-radiator whip antenna as in claim 18, wherein
said feed configuration is arranged to couple signals from
the first diplexer port to said outer element and signals from
the second diplexer port to said upper extension of the inner
conductor.
20. A dual-radiator whip antenna as in claim 18, wherein
said feed configuration includes

a lower feed circuit to couple signals from the first diplexer port to said outer element and signals from the second diplexer port to said inner conductor, and an upper feed circuit coupled between the upper terminus of the outer element and the upper extension of the inner conductor for excitation of said second radiating element. ⁵

21. A dual radiator whip antenna, comprising:

a vertically-extending concentric structure including ¹⁰
an outer element circumferentially surrounding an inner conductor, said outer element configured to provide a first radiating element operable over a first frequency band,

the inner conductor having an upper extension extending vertically beyond the upper terminus of the outer element, said upper extension configured to provide a second radiating element operable over a second frequency band; and ¹⁵

a feed configuration to couple first signals within the first ²⁰ frequency band to said outer element and couple second signals within the second frequency band to said upper extension, the feed configuration including

a diplexer coupled to an antenna port to separate signals into said first signals at a first diplexer port and said ²⁵ second signals at a second diplexer port,

a lower feed circuit at the base of said antenna to couple signals from the first diplexer port to said outer element and signals from the second diplexer port to said inner conductor, and ³⁰

an upper feed circuit coupled between the upper terminus of the outer element and the upper extension of the inner conductor to excite said second radiating element;

said outer element configured to form a monopole radiating element and said upper extension configured to form a ³⁵

dipole radiating element comprising said upper extension and an upper length of said outer element; and the outer element including, below said upper length, a choke circuit to improve isolation of second frequency band signals from transmission along said outer element below said upper length thereof.

22. A dual-radiator whip antenna, comprising:

a vertically-extending concentric structure including ¹⁰
an outer element at least partially surrounding an inner conductor, said outer element configured to provide a first radiating element operable over a first frequency band,

the inner conductor having an upper extension extending vertically beyond the upper terminus of the outer element, said upper extension configured to provide a second radiating element operable over a second frequency band; and ¹⁵

a feed configuration to couple first signals within the first frequency band to said outer element and couple second signals within the second frequency band to said upper extension of the inner conductor;

said outer element configured to form a monopole radiating element and said upper extension configured to form a dipole radiating element comprising said upper extension and an upper length of said outer element; and ²⁰

the outer element including, below said upper length, a choke circuit to improve isolation of second frequency band signals from transmission along said outer element below said upper length thereof. ²⁵
